Primary Examiner — Samantha Wood*Assistant Examiner* — Emily A Caven(57) CLAIM

The ornamental design for a toy for pets, as shown and described.

DESCRIPTION

FIG. 1 is a front perspective view of a toy for pets showing my new design.

FIG. 2 is another perspective view of an alternate configuration thereof.

FIG. 3 is a front view thereof.

FIG. 4 is a rear view thereof.

FIG. 5 is a left view thereof.

FIG. 6 is a right view thereof.

FIG. 7 is a top view thereof; and,

FIG. 8 is a bottom view thereof.

The broken lines depict portions of the toy for pets that form no part of the claimed design.

1 Claim, 8 Drawing Sheets(56)
